UNITED STATES PATENT OFFICE.

WILLIAM WESLEY KATTERJOHN, OF HENDERSON, KENTUCKY.

CANDLE OR LAMP HOLDER.

No. 928,131.

Specification of Letters Patent.

Patented July 13, 1909.

Application filed January 27, 1909. Serial No. 474,540.

To all whom it may concern:

Be it known that I, WILLIAM WESLEY KATTERJOHN, a citizen of the United States, residing at Henderson, in the county of Henderson and State of Kentucky, have invented new and useful Improvements in Candle or Lamp Holders, of which the following is a specification.

This invention relates to candle or lamp holders of the Christmas-tree type, the object of the invention being to provide a holder having a simple and inexpensive construction of fastening means for securing it to the limb of the tree, and which adapts the holder to be applied and removed in a ready and expeditious manner and insures the firm retention of the holder in position.

The invention consists of the features of construction, combination and arrangement 20 of parts hereinafter fully described and claimed, reference being had to the accompanying drawings, in which:—

Figure 1 is a perspective view showing the application of a candle holder embodying my invention. Fig. 2 is a vertical transverse section of the holder. Fig. 3 is a similar section taken at right angles to the section shown in Fig. 2. Fig. 4 is a detail fragmentary transverse section, showing a modified 30 way of fastening the ends of the fastening device to the body of the holder. Fig. 5 is a sectional elevation, showing another modified mode of securing the ends of the fastening device. Fig. 6 is a fragmentary plan view of the construction shown in Fig. 5. Figs. 7 and 8 are fragmentary and sectional views showing still another modified mode 40 of securing the ends of the fastening device. Fig. 9 is an elevational view illustrating the application of the invention to an electric lamp.

Referring to Figs. 1, 2 and 3, a candle holder of ordinary form is shown comprising a body 1 carrying a candle receiving 45 socket 2. The body 1 is in the form of a basal disk having corrugations around its edges, so that portions of the edges of the disk project upwardly at an oblique angle to the body of the disk, as shown in Fig. 2. The socket 2 is illustrated as being formed 50 of a slotted metal strip bent into circular shape and provided at its lower end with tongues passing through slits in the body or disk and clenched against the under side 55 thereof to secure the holder to the disk. This type of candle holder is preferably em-

ployed, although the invention may be applied to any other suitable type.

In accordance with the invention, a novel construction of fastening device is arranged 60 upon the under side of the base 1 of the holder for securing the latter to the limb of the tree. This fastening device consists of a transversely extending spiral spring 3 having its end portions 4 extending upward and 65 bent outwardly at an oblique angle to form bearing arms 5 having inwardly bent engaging hooks 6.

In practice, the spring contacts lightly with the under side of the base or disk and 70 is of less length than the diameter of the same, so that the arms 5 will bear against the bottom surface of the edge of the disk at opposite sides thereof, allowing the hooks 6 to be engaged with the edge of the disk and 75 to project inwardly over upon the top surface thereof. By this construction, the arms 5 will reinforce the hooks, which latter will be retained initially in position by the contractile energy of the spring, which latter 80 is applied to the holder in a slightly distended, sprung or stretched condition, so that it may easily and effectually adjust itself to variations in the sizes of the limbs of trees. This mode of applying the fastening 85 spring also insures the firm initial retention of the hooks in engaging position and while they are being permanently fastened. In practice, the arms and hooks are preferably arranged to respectively bear against and 90 rest in the surfaces and cavities of depressed portions of the corrugations, which will assist in holding the spring against lateral displacement. The ends of the spring may be firmly fastened in position, when a permanent fastening is necessary, by drops of 95 solder 7, which may directly fasten the hooks to the upper surface of the disk, as shown in Figs. 1, 2 and 3, or the arms to the lower surface of the disk, as shown in Fig. 4, in 100 which the arm at one end of the spring is represented as secured to the disk by a drop of solder 7'. It will be understood that this mode of applying the spring allows the coiled body portion of the spring to freely 105 expand and contract to engage different sizes of limbs to fasten the holder in position thereon, the limb passing transversely between any two adjacent coils and being gripped by the spring action thereof. The 110 slight normal distention of the spring not only increases its gripping action, and its

100
105
110

capability of adjusting itself to limbs of different sizes, but by fastening the ends of the spring to the body in the manner described, the engagement of the arms and hooks with the disk will be sufficiently secure to prevent transmission of undue strain to the solder, and even sufficient to hold the spring in operative position if the solder should become loosened and detached. It 10 will, of course, be understood that the spring fastener may be made of any suitable kind of spring wire or other material, and it will be seen that by its use the holder may be practically instantaneously applied and removed. 15

In Figs. 4 and 5 I have illustrated a different mode of fastening the hooked end of the spring, in which the portion of the wire forming each hook is extended, and the extension 8 bent with the body of the hook to form a coil or wrapping passing through a perforation 9 in the edge of the disk and enveloping the adjacent portion of the edge thereof. This construction secures a firm 20 mechanical fastening of the ends of the spring to the body of the holder without the use of solder or other like material liable to become loosened or displaced. 25

In Figs. 7 and 8 I have shown another 30 mode of fastening the ends of the spring in which each end of the spring is bent to form a laterally extending hooked portion 7^a, as indicated in dotted lines, the bill of which projects over the edge of the disk, on which 35 edge of the disk is formed a lug 10 having a tongue 11 adapted to be passed downward through an opening 12 in the disk. In securing the end of the spring, the lug 10 is bent over upon the portion 7^a, the tongue 11 40 properly bent and passed downward through the opening 12, and then said tongue is clenched against the under side of the disk, whereby the end of the spring will be securely held. 45

While the fastening device is designed primarily for use upon a candle holder as before described, it may also be used upon any other type of holder on which an illuminating device is mounted for attachment on a 50 limb of a Christmas-tree. In Fig. 9 I have shown a disk holder 1^a supporting an incandescent electric lamp 13 to which leads an electric feed wire 14. This disk is provided. 55 with beveled edges against which the arms of the spring bear, which spring is applied

in the manner shown in Fig. 1, but may be applied in any of the other ways disclosed. The fastener may also be applied to any other types of holders for securing ornaments of different kinds to the tree. 60

Having thus fully described the invention, what is claimed as new, is:—

1. A holder of the character described having a base piece, and a coiled spring fastener arranged transversely beneath the base piece, said spring having arms provided with bent terminals connected with opposite sides of the edge of the base piece and its coils held under tension. 65

2. A holder of the character described 70 having a base piece, a coiled spring fastener extending transversely beneath said base piece and having bent end portions interlocking therewith and holding said fastener, and auxiliary means fastening said 75 bent ends to said base piece.

3. A holder of the character described having a base piece provided with an upwardly inclined or beveled edge, and a coiled spring extending beneath said base piece, 80 said spring having inclined terminal arms engaging said beveled edge and provided with hooked extremities interlocked with said beveled edge.

4. A holder of the character described 85 having a base piece, and a fastener comprising a coiled spring extending beneath said base piece and having hooked ends engaging the edge of the base piece.

5. A holder of the character described 90 having a base piece, and a fastener comprising a coiled spring extending transversely beneath the base piece, said spring having its ends bent to form upwardly projecting arms provided with fastening members interlocked 95 with the marginal portions of the base piece.

6. A holder of the character described having a base piece, and a fastener comprising a coiled spring extending transversely beneath the base piece, said spring having its 100 ends secured to opposite sides of the edge of the base piece and its body portion held thereby under limited tension.

In testimony whereof I affix my signature in presence of two witnesses.

WM. WESLEY KATTERJOHN.
